UNITED STATES PATENT OFFICE.

OSCAR ROWLETT, OF MAYSVILLE, MISSOURI.

RAILROAD-TIE.

No. 905,234.

Specification of Letters Patent.

Patented Dec. 1, 1908.

Application filed August 16, 1907. Serial No. 388,884.

To all whom it may concern:

Be it known that I, OSCAR ROWLETT, a citizen of the United States, residing at Maysville, in the county of Dekalb and State of Missouri, have invented a new and useful Railroad-Tie, of which the following is a specification.

This invention relates to metal ties for supporting rails, more particularly on bridges, although they can as readily be employed on the ground as are wooden ties.

The object of the invention is to cast, roll or otherwise construct metal railroad ties, each having a central vertical web and a top and bottom horizontal flange, said ties having about the same dimensions as ordinary wooden ties.

To the ties are secured the railroad rails by novel connections, and the ties are in turn connected together by long bolts or rods passing through spacing pieces which regulate the distance between ties.

A further object of the invention is directed to the manner of fastening the ties to the bridge beams so that, while holding tightly thereto, they may be quickly released therefrom and from the rails and a new tie as easily substituted.

In the accompanying drawing:—Figure 1 is a horizontal cross section of a railroad track between two ties, showing the means used for fastening a tie to the bridge beams. Fig. 2 is a plan view of a portion of a track including three ties. Fig. 3 is a cross section on line 3—3 of Fig. 2.

Similar reference numerals are used for the same parts in all the figures.

The drawing illustrates the invention in use on a bridge wherein a small portion is shown such as two longitudinal I beams 1 and a tie beam 2 connecting them. The railroad ties 3 are placed across the bridge beams 1 and project beyond them equally at each end. Each tie 3 is forged, rolled or cast in the shape of an I beam, the upper and lower flanges lying in horizontal planes connected by a central vertical web 4 shorter at each end than the flanges and somewhat thicker than is found in commercial beams of like shape. Each tie 3 is fastened to the bridge beams 1 by means of L shaped lock bolts 5 which pass at each end vertically through the upper and lower flanges on one or both sides of the web 4 close to the top

flanges of the bridge beams 1 on their outer sides. The extended portions 6 of the lock bolts are placed under the upper flange of the bridge beams and fastened rigidly in place by nuts 7 on the upper end of the lock bolts, screwed hard against the ties 3.

In the longitudinal center of each tie is formed a series of spaced vertical apertures 8 in which are placed hook-shaped pins 9 wherever needed to hold railroad rails 10 in place. The hook-shaped pins 9 are held firmly in position by means of bolts or rivets 11 extending through holes 12 in the webs 4 and registering holes 13 in the pins 9. The sides of the pins 9 which enter the apertures 8, are preferably rectangular, the head of each having a projecting finger 14 which engages over the bottom flange of the rail or fish plate and by means of the connection, heretofore described, the rails are held securely fastened to the ties. Where an additional rail, as a switch rail, or a short section of straight rail forming a part of a turnout, for instance, lies close to the main rail, a pin 15 is used having a projecting finger 14 on each side of its head to engage both rails, see Fig. 1.

The ties are prevented from slipping or creeping on the beams by means of long bolts or rods 16 of varying lengths, some of which may extend from tie to tie only, while others may include an indefinite number of ties in their length. The bolts or rods 16 pass through the webs 4 of the ties near their ends and through spacing block or tubes 17 against the ends of which the ties abut. These spacing blocks are of equal length on a straight track thus keeping the ties at equal distances apart, but on a curved track, the outer blocks would be longer as understood. Below the rail seats of the main track 10 on the ties 3 are cross webs or flanges 18, each web extending vertically from flange to flange and horizontally from the web 4 to the outer limit of the flanges. These cross webs 18 are wider at the top than at the bottom, and are intended to give a firmer support to the rails. As heretofore stated the webs are shorter at each end than the upper and lower flanges thus leaving a space within each end of the tie. This space may be occupied by electric wires, cables, switch rods, pipes and other articles suitable to be placed therein. Through the upper

and lower flanges are holes 30 for use when the road using these ties is equipped with the block system of signaling.

Having thus described the invention what is claimed is:-

1. A railroad tie comprising an integral I beam having longitudinally spaced vertical apertures at each end extending through the web of said beam said web having also near its ends horizontal openings for connecting bolts or rods which join the ends of adjacent ties.

2. A railroad tie comprising an integral I beam, means for fastening rails thereto, spacing means between said beam and beams on each side thereof, and fastenings extending through said beams and the spacing means.

3. A railroad tie comprising an I-shaped beam having longitudinally spaced vertical apertures therein, tie bolts or rods for attaching said beam to beams on each side, space blocks or tubes on said bolts or rods, and means for fastening rails to said tie.

4. A railroad tie comprising an integral I beam the flanges of which project beyond the web at the ends and having spaced vertical apertures extending through the web from end to end and a horizontal bolt hole through the web at each aperture, and strengthening ribs between the upper and lower flanges at the points where the rails are seated.

5. A railroad tie comprising an I beam the flanges of which project beyond the web at the ends of the beam to form a housing or space for wires, said flanges having vertical openings therethrough at their outer ends for wires.

In testimony that I claim the foregoing as my own, I have hereto affixed my signature in the presence of two witnesses.

OSCAR ROWLETT.
